(57) **CLAIM**

The ornamental design for a scoop, as shown and described.

DESCRIPTION

FIG. 1 is a perspective view of scoop, embodying our new design;

FIG. 2 is a front view thereof;

FIG. 3 is a top plan view thereof;

FIG. 4 is a bottom view thereof;

FIG. 5 is a left side view thereof;

FIG. 6 is a right side view thereof;

FIG. 7 is a cross sectional view thereof;

FIG. 8 is a perspective view of a second embodiment of scoop, embodying our new design;

FIG. 9 is a front view thereof;

FIG. 10 is a top plan view thereof;

FIG. 11 is a bottom view thereof;

FIG. 12 is a left side view thereof;

FIG. 13 is a right side view thereof; and,

FIG. 14 is a cross sectional view thereof.

The broken lines shown in the drawings are for illustrative purposes only and form no part of the claimed design.

Back view is omitted because a back view is identical to a front view.
